[57] CLAIM

The ornamental design for a table, as shown and described.

DESCRIPTION

FIG. 1 is a perspective view of a table according to the present invention looking from the front, left side, and top;

FIG. 2 is a side view of the table of FIG. 1;

FIG. 3 is a front view of the table of FIG. 1, it being understood that the rear side of the table is identical to the front side; and,

FIG. 4 is an enlarged view of the leg of the table as depicted in FIG. 3.

FIG. 1

FIG. 2

FIG. 4

FIG. 3
